US00D598134S

(12) **United States Design Patent**
Davina et al.

(10) **Patent No.:** **US D598,134 S**
(45) **Date of Patent:** **** Aug. 11, 2009**

(54) **DOOR PANEL GROUPING**

(75) Inventors: **Glenn A. Davina**, Klamath Falls, OR (US); **Tom Brown**, Klamath Falls, OR (US); **James S. Hackett**, Klamath Falls, OR (US); **Rodney C. Harlin**, Sulphur Springs, TX (US); **Daniel S. Malicki**, Klamath Falls, OR (US); **John Monfore**, Klamath Falls, OR (US); **Craig R. Turner**, Klamath Falls, OR (US)

(73) Assignee: **Jeld-Wen, Inc.**, Klamath Falls, OR (US)

(**) Term: **14 Years**

(21) Appl. No.: **29/303,583**

(22) Filed: **Feb. 12, 2008**

(51) LOC (9) Cl. **25-02**

(52) U.S. Cl. **D25/48**

(57) **CLAIM**

We claim the ornamental design for a door panel, as shown and described.

DESCRIPTION

FIG. 1 is a front elevation view of a door panel of the present invention.

FIG. 2 is a front perspective view thereof; and,

FIG. 3 is a cross sectional view taken on line 3—3 of FIG. 1. Broken lines are for illustrative purposes and form no part of the claim.
